UNITED STATES PATENT OFFICE.

MILTON C. POWELL, OF CHICAGO, ILLINOIS, AND DWIGHT POWELL, OF BROCKTON, MASSACHUSETTS.

METAL CABINET STRUCTURE.

1,368,052.

Specification of Letters Patent.

Patented Feb. 8, 1921.

Application filed April 16, 1919. Serial No. 290,533.

To all whom it may concern:

Be it known that we, MILTON C. POWELL and DWIGHT POWELL, citizens of the United States, residing, respectively, at Chicago, in the county of Cook and State of Illinois, and at Brockton, in the county of Plymouth and State of Massachusetts, have invented certain new and useful Improvements in Metal Cabinet Structures, of which the following is a specification, reference being had to the accompanying drawings, forming a part thereof.

The purpose of this invention is to provide a system of construction for sheet metal cabinets which will so simplify the process of assembling the parts that, if desired, they can be shipped knocked-down and any workman of average intelligence can readily set up a cabinet of this type without the use of special tools or equipment. The invention comprises various features and elements of construction hereinafter described and shown in the drawings as indicated by the claims:

25 In the drawings:

Figure 1 is a perspective view of a cabinet embodying this invention with the parts fully assembled.

Fig. 2 is a broken and condensed vertical section taken from a plane within the cabinet shown in Fig. 1 and looking against the inner face of the side wall, the parts being shown on a larger scale than in Fig. 1 to indicate various details of construction.

35 Fig. 3 is a detail section taken as indicated at line 3—3 on Fig. 1.

Fig. 4 is a detail section taken as indicated at line 4—4 on Fig. 1.

40 Fig. 5 is a detail section taken as indicated at line 5—5 on Fig. 2.

Fig. 6 is a detail section of a modification of a corner construction corresponding to that shown in Fig. 3.

The cabinet shown for the purpose of illustrating this invention is designed for household use as a kitchen cabinet having a series of shelves in its upper portion for storage of dishes and supplies and a deep drawer in its lower portion with a clear space above said drawer and below the shelves in which there may be installed a stove or oven for cooking. The structural details with which the invention is concerned are applicable however to a large

variety of cabinets, boxes or receptacles, made principally of sheet metal.

In the cabinet shown the back wall, 1, consists of a single relatively thin sheet of metal with corner posts consisting of steel angles, 2, secured to its lateral margin preferably by spot welding as at 2^a, as indicated in Figs. 3 and 4. The front panel of the cabinet consists of corner posts in the form of channel rails, 3, 3, opening rearwardly and transversely connected by horizontal angle bars, 4, 5 and 6, respectively, lodged in notches in the inner flanges, 3^a, of the channel, 3, and with their vertically extending and longer legs, 4^a, 5^a and 6^a, respectively spot welded against the inner face of the web of each channel, 3.

The front and back sections of the cabinet thus formed are connected together by side sheets 7, 7, each consisting of a single sheet of thin metal with its vertically extending lateral margins in contact with the inner faces respectively of the flange, 2^b, of the angle, 2, and the flange, 3^b, of the channel, 3. In the vicinity of the shelves, 8, these flanges, 2^b and 3^b, of the corner posts are provided with offset lugs or abutments, 9, as shown in Fig. 3, and near its lateral margin the side sheet, 7, is formed with apertures or recesses shown as louver openings, 10. Since the angle, 2, is permanently welded to the back wall, 1, its flange, 2^b, is in effect a flange of said wall, and with the abutments, 9, facing toward the wall, 1, and engaging the edges of the recesses or apertures at 10, they thus retain the side sheet, 7, against separation from the back wall, 1; and similarly with each abutment, 9, of the flange, 3^b, facing the web of the channel, 3, and engaging the edge of the louver opening at 10, the side sheet, 7, is likewise retained against withdrawal from its position in the channel, 3, as shown in Fig. 3. Assembly of the parts in this relation is accomplished by merely placing the side sheet in contact with the flanges, 2^b and 3^b, of the corner posts, and then inserting the shelves, 8, in the cabinet, first engaging their front edges with the notches, 11, formed for them in flanges, 3^a, of the channel, 3, and then swinging the shelves to horizontal position; being of definitely calculated length in relation to the width of the back panel, 1, they act as spreaders to maintain engagement of

95

100

105

the lugs, 9, with the louver recesses, 10, thus locking the four walls of the cabinet together.

It will be understood that the lugs or abutments, 9, and recesses, 10, need not be formed in the particular way shown in Fig. 3. Fig. 6 suggests a modification in which the side sheet, 7^a, is provided with suitable recesses by making clean cut apertures, 12, while a disk, 13, of the flange, X, of the corner post shown is forced or punched part way through the metal of the flange thus forming an embossment or projecting lug to engage the aperture, 12.

15 As the rear edges of the shelves, 8, are swung downwardly against the back wall, 1, bringing the shelves to horizontal position, the depending flange of each shelf, 8, shown at 14, in Fig. 2, enters an upwardly open channel formed by an offset strip, 15, welded across the back wall, 1. Preferably this strip, 15, is thin enough to yield away from the plane of the wall, 1, and it is formed with louver openings, 16, to receive 20 similar features, 17, acting as abutments on the flange, 14, of the shelf, 8, to lock the flange into the offset strip, 15, so as to hold the shelf securely in place. The bottom shelf, 18, of the upper compartment of the 25 cabinet containing the shelves, 8, is shown with a somewhat deeper flange, 19, which instead of being lodged in one of the notches, 17, in the channel flange, 3^a, rests on the transverse angle bar, 5, immediately back of its vertical flange, 5^a, as indicated in Fig. 2. At the rear, the shelf, 18, is provided with a depending flange, 14, locked in engagement with a supporting strip, 15, in the same way as shelves, 8.

40 As the foregoing system of assembly for the side and back walls depends upon the presence of spreader members, such as the shelves, 8, it can not be so well applied to the portion of the wall inclosing the clear 45 space below the shelved cupboard. Here the back wall, 1, is formed with a flange, 1^a, extending forwardly and parallel to the flange, 2^b, of the corner post, 2, and spaced slightly away from said flange far enough 50 to admit the thickness of the side sheet, 7. The louver openings, 20, or other form of abutments provided in the side sheet, 7, face away from the plane of the side wall, 1, and correspondingly formed louver openings, 55 21, constituting recesses in the flanges, 1^a, are positioned to receive said lugs or abutments, 20, when the edge of each sheet, 7, is inserted between the flanges, 1^a and 2^b, the flange, 1^a, yielding slightly to permit 60 entrance of the extending abutments, 20, and then snapping back to lock the louvers, 20 and 21, in nested relation. A similar expedient is employed at the front corner post by welding to the web of each of the channels, 3, a flanged strip, 22, whose flange, 23,

extends parallel to the flange, 3^b, of the channel, 3, and is formed with louver openings or recesses, 24, to receive the corresponding features, 25, on the side sheet, 7. Thus it will be understood that, in assembling a cabinet constructed as shown herein, the marginal portions of the side sheet, 7, just described, will first be engaged and snapped into locked position between the corner posts and the yieldable locking flanges, 1^a and 2^b, which are illustrated in Fig. 4, and this engagement will give the cabinet a temporary stability, facilitating the insertion of the shelves, 8, for completing the engagement of the side walls with the front and back panels.

Hinged doors, 26, are shown for inclosing the cupboard section which is fitted with the shelves, 8, while a drawer, 27, is provided at the lower part below the shelf, 28, which may be substantially similar to the shelves, 8, in its dimensions and mode of securement.

At the top, the parts are firmly held in proper relation by a cap, 29, having a depending front flange, 30, whose inturned edge, 31, yieldingly rides over and locks against an abutment, 32, formed in the front of each of the channels, 3, while at the rear edge of said cap, 29, a depending flange, 33, is locked in engagement with the back wall by its abutment, 34, nested with louver openings, 35, in the upper marginal portion of said wall, 1. A flange, 36, at each end of the cap, 29, overhangs the side wall, 7, as shown in Fig. 5, while an inclined strip, 37, with its flange, 38, spaced away from the flange, 36, to admit the edge of the side sheet, 7, engages the inner face of said side sheet to more definitely position it, as shown in Fig. 5.

We claim:

1. A metal cabinet comprising a front section and a back section each having marginal flanges, said flanges having offset lugs or abutments on their inner faces, side sheets with recesses positioned to register with such abutments and horizontally-extending members dimensioned to extend between the opposite side sheets and maintain engagement of their said recesses with the abutments of the front and back sections.

2. In a metal cabinet, a wall having opposite marginal flanges and two transverse walls disposed respectively in contact with the inner faces of said flanges, each flange having one or more inwardly-projecting lugs or abutments, and the transverse walls having recesses registering with and engaging said abutments and a member dimensioned to extend between said marginal flanges with said transverse walls interposed for maintaining their engagement with the said flanges.

3. In the structure defined in claim 2, the

abutments being formed by embossments pressed in the material of said flanges.

4. In the structure defined in claim 2, the flanges being formed of angle rails, each 5 having one leg permanently attached to the margin of a sheet constituting said wall.

5. In the structure defined in claim 1, the said abutments on the flanges facing back toward the respective sections to which 10 said flanges pertain, whereby the side sheets serve to tie together the front and back sections.

6. In a metal cabinet, a wall having a flange and a transverse wall with its marginal portion in contact with said flange, the flange having one or more projecting lugs or abutments, and said transverse wall having recesses registering with and engaging such abutments, together with a member 20 unattached to said transverse wall but extending into contact therewith on the opposite side from said flange, said member being engaged with the first mentioned wall at a point remote from the transverse wall, 25 and thus positioned for holding said two walls in connected relation therewith.

7. In a metal cabinet, a joint composed of a pair of flanges spaced apart, and a wall having its marginal portion inserted between said flanges, one of said parts having one or more lugs or abutments, and another of said parts having one or more recesses positioned to register with such abutments, one of the flanges being relatively rigid, and the 35 other adapted to yield with respect thereto for admitting the marginal portions of the wall between them.

8. In a metal cabinet, a joint composed of a pair of flanges spaced apart and a wall 40 having its marginal portion inserted between said flanges, the wall and one of said flanges having one or more pairs of oppositely facing abutments adapted for mutual engagement for retention of the wall margin 45 between said flanges.

9. In the combination set out in claim 8, one of the flanges being adapted to yield and one set of abutments having sloping approaches for spreading the flanges upon 50 entry of the wall margin.

10. In a metal cabinet, means for connect-

ing transverse walls, comprising a pair of flanges both extending from one wall in the same direction, and spaced apart sufficiently to receive the thickness of the other wall between them, said wall having one or more abutments on its marginal portion embraced by said flanges, one of the flanges having recesses registering with and engaging such abutments respectively, and one of the 55 flanges being yieldingly supported on its wall to permit entry of the other wall with its lugs or abutments between the flanges.

11. In a metal cabinet as defined in claim 10, said abutments facing away from the 60 flanged wall to engage the recesses of said flanges as hooks to resist separation of the two walls.

12. In a metal cabinet as defined in claim 10, the abutments of the wall and the recesses of the flange being formed as louver openings pressed up in the material and nested when assembled, with the up-raised cut edges of said openings facing away from the flanged wall. 75

13. In a metal cabinet as defined in claim 2, the abutments of the flanges and the recesses of the transverse walls being formed as louver openings pressed up in the material and nested when assembled, the up-raised cut edges of said openings facing toward the flanged wall. 80

14. In a metal cabinet, front corner posts of channel shape opening rearwardly with their inner flanges notched to receive the 85 front edge of a shelf, the shelf lodged therein having a depending flange at its rear edge in contact with the rear panel of the cabinet, a member extending parallel to said rear panel and spaced from it sufficiently to admit the flange of the shelf, said member and said flange having registered louver openings with their offset cut edges facing toward the under side of the shelf. 90

In testimony whereof, we have hereunto 95 set our hands at Chicago, Illinois, and at Brockton, Massachusetts, respectively, this 29th day of March, 1919, and the 31st day of March, 1919.

MILTON C. POWELL.
